UNITED STATES PATENT OFFICE.

RALPH J. DORION, OF BINGHAMTON, NEW YORK.

PRINTING FORM.

Application filed May 1, 1923. Serial No. 636,010.

To all whom it may concern:

Be it known that I, RALPH J. DORION, citizen of the United States, residing at Binghamton, in the county of Broome and

5 State of New York, have invented certain new and useful Improvements in Printing Forms, of which the following is a specification.

This invention relates to printing, and more particularly to a novel printing form 10 whereby tags of the character used in shoe factories for checking the making of shoes may be readily printed.

In the manufacture of shoes, it has been the general custom to use a tag having 15 printed thereon the various operations involved in the making of a shoe. These tags accompany the shoes throughout their process of making and the data of each operation is arranged in such a way as to provide 20 a coupon which is cut off by the operator after the completion of his work and retained by him as a receipt or check upon which to collect his wages at the end of the earning period. Heretofore, each coupon 25 on the tag was provided with a punch mark indicating the price that the operator was to receive for his particular operation on the shoe, and for various reasons this method has been found objectionable. For 30 example, a separate punch is required to make the separate symbols indicating the price for the various operations. Therefore, a large number of punches must be kept on hand and a special operator is re- 35 quired to punch the tags with the proper price symbols before they are distributed to the operators. This practice is also open to the objection that operators can sometimes make alterations in the price marks which 40 would increase the rate of pay for the particular operation, thereby defrauding the manufacturer on the amount paid for services or wages.

Having in view the above objections and 45 difficulties, the present invention aims to provide means for printing a tag which has thereon a plurality of coupons each bearing the price definitely and plainly printed, thereon in such a way that there is no possibility of alteration; and which, furthermore, provides for assembling the printing type for each particular room or station, through which the shoe proceeds in the process of manufacture, within one frame so 50 that the order of the coupons may be preserved for reuse in printing up subsequent

60 tickets, thus obviating the necessity of entirely re-setting the coupons within a particular frame when the same shoe is again ordered.

65 In its general aspect, therefore, the present invention proposee to provide a printing form comprising a plurality of coupon frames containing printing types for printing the individual coupons in their proper order and maintaining the type locked in position so that the frame may be handled as a unit and manipulated as desired to be 70 properly placed within the usual chase. In that connection it may be noted that these frames may be removed from the chase after the tags have been printed and the individual frames classified and filed away to be available for re-use, as above indicated. As the operations will be repeated 75 for the same shoe it will be clear that the same coupons may be used, and as the price, for the grater part of the time at least, also remains the same, the price line of each coupon may also be used. In the event 80 however, that the operator is allowed a different rate than the previous price, it is only necessary to change the slug forming the price line without requiring a re-setting of all of the type within the frame. 85 Thus, it will be apparent that the invention obtains maximum economy in the printing of shoe tags.

90 With the above and other objects in view which will more readily appear as the nature of the invention is better understood, the same consists in the novel construction, combination and arrangement of parts hereinafter more fully described, illustrated and claimed.

95 A preferred and practical embodiment of the invention is illustrated in the accompanying drawings, in which:—

100 Figure 1 is a plan view of the present printing form set up within a chase.

Figure 2 is a detail perspective view of one of the coupon frames.

Figure 3 shows one of the tags printed by the form shown in Fig. 1.

Figure 4 is a detailed sectional view taken 105 on the line 4—4 of Fig. 1.

Similar reference characters designate corresponding parts throughout the several figures of the drawings.

110 As previously indicated it is the purpose of the present invention to provide a printing form that will print a tag which may

be distributed direct to the operator with each order as it goes through the factory without the necessity of subjecting the tag to any operation other than placing it in the 5 usual case numbering machine which all of the tags must go through to receive the number of the order and the number of pairs of shoes so that the individual coupons may be properly identified after they 10 are severed from the tag by the operators upon finishing of each operation.

As the case numbering machine writes its data in lineal spaced intervals, it is necessary to keep the arrangement and spacing 15 of the coupons in harmony with the spacing of the case numbering machine, because after the operator has set the machine in operation, it automatically feeds the tags and prints the case numbers and pair numbers 20 on each coupon.

Heretofore in the printing up of shoe tags some space on the tag had to be wasted in order to keep the coupons properly aligned in opposite columns so that all of the 25 coupons could be properly numbered by the case numbering machine.

Also in the past it was necessary to print more operations on the tag than might be used for each particular shoe so that the 30 same tag would do for a number of styles of shoes. That is to say, since shoes of different style and type do not require identical operations, and it was desirable to make one tag satisfy as many types as possible 35 it was necessary to print all of the likely operations on the tag and then the operator who handled the price punch would simply punch the coupons which indicated the operations to be performed on a particular shoe 40 in the process of manufacture. Thus, some coupons would be left unpunched and were useless for that particular shoe, but there was always the possibility of these unpunched coupons being fraudulently punched 45 and turned in for cash. However, by the use of the present invention, which contemplates a printing form for only printing precisely the operations required on each particular shoe, and definitely printing the 50 price, the possibility of spare coupons being out is eliminated and also the necessity of useless printing is avoided.

Fig. 3 of the drawings shows a tag T printed from the form shown in Fig. 1, and 55 it will be observed that the upper part of the tag bears printed matter known as the "description" of the shoe and designated "A" while beneath the description A are parallel columns of coupons B. Each coupon is 60 defined by the lines or rules B' and it will be observed that lines in each column defining the coupons are directly opposite. In order to maintain the proper spacing of the coupons although the operations in opposite 65 columns may not be the same in number it

is necessary to provide at intervals "killers" C which will fill up the otherwise blank space on the tag to prevent fraud or the use of that particular section of the tag as a coupon when it is severed from the main 70 body of the tag.

As will presently appear these killers C may be in different forms according to the position that the space would occur in the printing form. For example the first step 75 in making a shoe takes place in the cutting room which is represented by the coupons D in Fig. 3, and since the tag would have a blank space opposite the three coupons for the cutting room that portion of the tag lying opposite the coupons D is provided with killers C' so that when the coupons D are cut off from the tag, no blank portions will appear.

After the shoe leaves the cutting room it 80 proceeds to the stitching room wherein the coupons E are severed, each coupon representing an operation in the stitching room.

After leaving the stitching room the shoe 85 passes to the assembling room and the coupons F are removed and then the shoe proceeds to the lasting room where coupons G are removed, etc.

Between the coupons representing the operations of each room the killers C are 90 arranged, and if any individual coupon is intended to be "killed" the type of killers shown at C' are used.

As will also be observed from Fig. 3 each 95 coupon bears a legend B² designating the operation, such for example as "skive heel" and the price legend B³, namely, "*9—10*".

Also the top or last coupon to be cut off in each series of operations bears an identification symbol B⁴ indicating the room in 100 which the operation takes place; the kind or pattern of shoe; and also providing an index to the price schedule that the operator receives for the particular operations on that shoe. This identification is important because it serves as an index number for filing 105 away the frames and types constituting the coupon units after they have been used.

Referring now to the printing form for 110 printing the type of tag shown in Fig. 3 it is pointed out that the same essentially comprises a plurality of rectangular type holding frames 1 adapted to hold the rows or lines of type 2 together with the rules 115 3 which define the individual coupons. These printing frames may be provided with a set screw 1^a as shown in Fig. 2 for clamping the rows of type in the frame to provide 120 the coupon unit which may be handled as a whole and freely manipulated without disturbing the set-up of the type therein.

The said printing frames 1 may be of any 125 desired size according to the number of coupons required to represent the number of operations to be performed on the shoe in 130

each room or station. For instance, in the cutting room, for the particular style of shoe shown in the drawing only three operations are involved, while in the stitching room nineteen operations are involved, thus requiring nineteen coupons which can best be set up within separate parallel frames of nine and ten each respectively. Between the narrow ends of the printing frames suitable killer type 4, as clearly shown in Fig. 4, may be used, the said killer type serving the purpose heretofore indicated, and at this point it may be noted that the width of the narrow end of each frame plus the killer type is just the width of the coupon so that when the frames are placed end to end in their proper order, the killer type will be the width of one coupon thus preserving the proper spacing and sequence of the coupon throughout the tag.

It will be apparent that the provision of the coupon frames is a comparatively simple and inexpensive matter and the coupons to be held therein may be formed by type made on a standard linotype machine, thereby being easily and quickly set up in an ordinary printing establishment without special facilities. Furthermore, if it becomes necessary to change a particular line of the coupons this may be readily accomplished by making a new type slug and substituting it for the one to be removed.

Also as previously indicated the upper coupon of each unit, or the last coupon to be severed is provided with an identification symbol B⁴ which furnishes a key to the particular type or style of shoe to which the operations of that unit relate, thereby making it possible for each individual coupon unit to be also identified after it is removed from the chase. This is an important feature of the invention because it makes possible the re-use of the coupon unit after the tags for a particular style of shoe have been printed, without the necessity of maintaining the type forms fully set up and standing about, thereby occupying much valuable storage space. That is to say, after a tag has been printed the individual coupon units may be taken out of the chase and filed away on racks or shelves, properly classified and then when a repeat order comes in for a particular shoe the type for each operation will already be set, and a clerk can reassemble all of the coupon units necessary for printing the tag without requiring a printer to make new type and entirely reset the tag. As many of the operations in a shoe are standard, it will be apparent that many of the coupon units may be used over and over again, and also as the price that each operator receives is fixed by wage agreements which usually last for some time, that also remains the same thus making it possible to re-use the coupons without difficulty.

From the foregoing it will be apparent that the present invention contemplates a printing form for factory tags comprising a plurality of type holding frames 1 which are adapted to be disposed in a row within a common chase 5, each of the said type holding frames constituting a coupon unit containing the coupon printing types 2 consecutively arranged corresponding to the successive operations in the manufacture of a shoe, together with the killer printing types 4 arranged between all of the printing frames to prevent fraudulent operation of the printing tag.

In connection with the coupon printing types it is pointed out that the index or identification symbol B⁴ is co-related with the data found in the description A of the form which gives the full data about the shoe. Thus, the individual coupon units may be readily identified through the medium of this index symbol after they have been removed from the form, thereby making their re-use easy when desired.

Without further description, it is thought that the many features and advantages of the invention will be readily apparent to those skilled in the art, and it will, of course, be understood that changes in the form, proportion, and minor details of construction may be resorted to without departing from the spirit of the invention or scope of the appended claims.

I claim:

1. A printing form for factory tags comprising a plurality of type holding frames disposed in a row within a common chase, each of said frames containing coupon printing types consecutively arranged corresponding to successive operations in the manufacture of a shoe, and killer printing types arranged between all of the frames to prevent fraudulent alteration of the printing tag.

2. A printing form for factory tags comprising a plurality of type holding frames disposed in a row within a common chase, each of said frames containing coupon printing types consecutively arranged according to the successive operations of the manufacture of a shoe, an identification symbol carried by one of the coupon printing types, and killer printing types arranged between the frames to occupy the space of a coupon and thereby prevent fraudulent alteration of the tag.

3. A printing form for factory tags comprising a plurality of type holding frames adapted to be arranged end to end within a common chase, coupon printing types consecutively arranged within the frame, and killer printing type arranged between the narrow end of the frame to occupy the space of a coupon.

4. A printing form for factory tags com-

- prising a plurality of removable and replaceable type holding frames having coupon printing types therein, and certain of said types bearing an index symbol.
5. A printing form for factory tags comprising a rectangular type holding frame, a plurality of lines of printing types set up within the frame and arranged to provide coupons arranged in successive order, and 10 means for locking the lines of type within the frame.
6. A printing form for factory tags, comprising a plurality of rectangular frames, a plurality of type slugs arranged in said 15 frames to provide coupons bearing unalterable data and means for locking said slugs in the frames.
7. A printing form for factory tags comprising type for printing a description of 20 the article to be manufactured, a plurality of coupon units each bearing an identifica-

tion symbol co-related to the description whereby the said coupon units may be removed and subsequently reassembled in the proper order.

25 8. A printing form for factory tags comprising type for printing a description of the article to be manufactured, a plurality of coupon units each arranged in successive order according to the successive operations of 30 the article being manufactured, bearing an identification symbol co-related to the description whereby the said coupon units may be removed and subsequently reassembled in the proper order.

35 In testimony whereof I hereunto affix my signature in the presence of two witnesses.

RALPH J. DORION.
